VALVE REMOVING TOOL

Filed June 27, 1950

FIG. 1

FIG. 2

UNITED STATES PATENT OFFICE

2,632,238

VALVE REMOVING TOOL

David Dyck, Hudson Bay, Saskatchewan,
Canada

Application June 27, 1950, Serial No. 170,539

2 Claims. (Cl. 29—215)

1

This invention relates to a disassembling device and more particularly to a device for removing valve assemblies.

An object of this invention is to provide a valve removing tool which may be utilized to dislodge valve assemblies from the blocks of internal combustion engines.

Another object of this invention is to provide a valve removing tool which may be utilized to dislodge valve assemblies from the blocks of internal combustion engines with speed and facility without impairing the valve assembly.

A further object of this invention is to provide a valve removing tool which is simple in structure and cheap to manufacture.

Other objects of this invention will become apparent from consulting the following specification in conjunction with the drawings.

In the drawings:

Figure 1 is a side elevational view with parts in section of the valve removing tool of the present invention in its contracted position as applied to a valve assembly at the beginning of its removal from a block of an internal combustion engine.

Figure 2 is a side elevational view of the tool as applied in Figure 1 but showing the tool in its extended position and the valve assembly at the end of its removal from a block of an internal combustion engine.

Figure 3 is an enlarged perspective view of the valve disassembling tool of the present invention, with parts broken away and in section.

Referring now more particularly to the drawings wherein like reference numerals have been used throughout the several views to designate like parts, there is shown the valve removing tool of the present invention, generally designated by the numeral 10, as applied to the valve assembly 11, which is seated in the block 12 of an internal combustion engine.

The block 12 of the internal combustion engine, which is generally illustrated as the Ford type, includes a pair of confronting bores 14, 15 which are readily accessible to the mechanic upon removal of the cover of the block 12, not shown. Disposed within the bores 14, 15 is a conventional valve assembly 11 which includes a bushing 16 disposed within the bore 14 and a valve stem 17 reciprocable in the bushing 16 and carrying a valve head 18 which is normally urged into seating engagement with the seat 19 by a valve spring 20, the spring being circumposed about the stem 17 between a shoulder 24 on the bushing 16 and an abutment 21 on the lower end of the stem 17.

2

Disposed within the bore 15 in aligned abutting relation with the stem 17 is a cam follower 25 which is reciprocated by a cam 22 carried by the cam shaft 23 of the internal combustion engine.

The aforementioned structure of the valve assembly 11 and the cam actuating means is entirely conventional and forms no part of the valve disassembling tool of the present invention, which 10 includes a pair of arms 30, 31 disposed in spaced confronting relation with respect to each other and pivotally connected together at one end thereof for movement toward and away from each other. Each of the arms 30, 31 is of like 15 structure and includes a shank 32, 33 having an inwardly extending web 34, 35 carried at one end thereof, and an inwardly converging force applying member 36, 37 carried at the other end thereof. The free ends of the force applying 20 members 36, 37 are offset with respect to the main portion thereof and form bearing plates, 38, 39.

It is to be noted that the respective webs 34, 35 are disposed at right angles with respect to 25 the shanks 32, 33 and are arranged in end to end abutting relation with respect to each other, the abutting ends of the webs 34, 35 being rounded as indicated at 40, 41.

Disposed exteriorly of the arms 30, 31 and 30 operatively connected thereto is an arcuate leaf spring 42, the spring having one end extending toward the web 34 of the arm 30 and secured thereto, and having the other end extending toward the web 35 of the arm 31 and secured thereto. The spring 42 normally biases the confronting bearing plates 38 and 39 into abutting engagement with respect to each other.

The respective aligned webs 34, 35, the spaced shanks 32, 33 and the converging force applying members 36, 37 cooperate to form an elongated 40 longitudinally extending opening 43 in which is slidably received an actuating means, generally designated by the numeral 44 for urging the bearing plates 38, 39 out of bearing engagement with respect to each other.

The actuating means 44 includes a plunger 45 disposed longitudinally of the arms 30, 31 and slidably received and supported in aligned spaced apertures 46, 47 provided in the confronting ends of the webs 34, 35 of the arms 30, 31 and in the leaf spring 42 respectively. One end of the plunger 45 is disposed exteriorly of the arms 30, 31 and the spring 42 and is provided with a finger piece 48. The other end of the plunger 45 is disposed within the opening 43 and carries a spherical ball 49 which is adapted to

bear against the adjacent inner faces of the force applying members 36, 37. Accordingly as the plunger 45 is moved longitudinally of the opening 43, the ball 49 urges the force applying members 36, 37 away from each other.

Circumposed about the plunger 45 within the opening 43 is a coil spring 50, the spring having one end bearing against the adjacent inner faces of the webs 34, 35 and having the other end bearing against the ball 49. The spring 50 normally urges the ball 49 into bearing engagement with the abutting faces of the bearing plates 38, 39. It is to be noted that when the ball 49 is disposed intermediate the bearing plates 38, 39, as clearly illustrated in Figures 2 and 3, forces applied normal to the plates will not urge the plates back into abutting engagement with each other. Accordingly the bearing plates will be maintained in spaced apart relation with respect to each other until the ball 49 is retracted from between the plates.

In actual use, the cam shaft 23 is rotated until the lobe of the cam 22 lifts the cam follower 25, resulting in the raising of the valve head 18 out of seating engagement with the valve seat 19. The valve head 18 is then held in this position, as indicated in Figure 1, while the cam 23 is being rotated to the full line position shown therein, whereupon the bearing plates 38, 39 of the valve disassembling tool 10 can be inserted between the confronting ends of the valve stem 17 and the cam follower 21. The cam shaft 23 is once again rotated until the lobe of the cam 22 lifts the cam follower 25. During the last named rotation an upwardly directed force is exerted on the bushing 16 through the cam follower 21, the bearing plates 38, 39, and the valve stem and spring. This upwardly directed force partially urges the bushing out of the bore 14.

Upon once again rotating the cam shaft 23 to the full line position shown in Figure 1, the cam follower 21 will slide downwardly and the resiliency of the coil spring 50 will urge the ball 49 into its position intermediate and bearing against the confronting faces of the bearing plates 38, 39. During the subsequent rotation of the cam 22 to the position shown in Figure 2, an upwardly directed force is again applied to the valve assembly 11, whereupon the bushing 16 is urged out of the bore 14. Accordingly the valve assembly 11 can be removed with speed and facility and be replaced and repaired.

Although only one embodiment of the invention has been shown, numerous other modifications may be made without departing from the spirit of the invention as set forth in the appended claims.

What I claim is:

1. A valve removing tool comprising a pair of

arms arranged in spaced confronting relation, a web positioned transversely of each of said arms adjacent one end of said arms and fixedly secured thereto, said webs facing and abutting each other, a bowed leaf spring arranged longitudinally exteriorly of and straddling said webs and having its ends fixedly connected to said webs, a rod positioned longitudinally of and between said arms and having one end slidably supported in the abutting point of said webs and in said leaf spring and projecting beyond said leaf spring, a ball positioned between said arms and spaced from said webs and fixedly secured to said rod, a bearing plate on the other end of each of said arms, said plates facing each other and engaging said ball, a spring operatively connected to said rod for biasing said ball toward its position of engagement between said bearing plates, and a head on the projecting end of said rod abutting the leaf spring when the ball is in its position of engagement between said bearing plates.

2. A valve removing tool comprising a pair of arms arranged in spaced confronting relation, a web positioned transversely of each of said arms adjacent one end of said arms and fixedly secured thereto, said webs facing and abutting each other, a bowed leaf spring arranged longitudinally exteriorly of and straddling said webs and having its ends fixedly connected to said webs, a rod positioned longitudinally of and between said arms and having one end slidably supported in the abutting point of said webs and in said leaf spring and projecting beyond said leaf spring, a ball positioned between said arms and spaced from said webs and fixedly secured to said rod, a bearing plate arranged at an angle with respect to each arm and fixedly secured adjacent the other end of said arms, said plates facing each other and engaging said ball, a spring operatively connected to said rod for biasing said ball toward its position of engagement between said bearing plates, and a head on the projecting end of said rod abutting the leaf spring when the ball is in its position of engagement between said bearing plates.
